PONY CART

John W. See, Martinsville, Ind.

Application March 24, 1958, Serial No. 50,165

Term of patent 14 years

(Cl. D14—3)

Fig. 1 is a perspective view from the right-hand side of a pony cart embodying my new design.

Fig. 2 is a fragmentary perspective view from the left-hand side thereof.

The shafts are shown broken away to indicate indeterminate length.

I claim:

The ornamental design for a pony cart, as shown and described.
